MARTIN EKENBERG, OF STOCKHOLM, SWEDEN, ASSIGNOR TO MARTIN EKENBERGS AKTIEBOLAG, OF STOCKHOLM, SWEDEN.

VACUUM APPARATUS.

SPECIFICATION forming part of Letters Patent No. 774,054, dated November 1, 1904.

Application filed October 30, 1902. Serial No. 129,342. (No model.)

To all whom it may concern:

Be it known that I, MARTIN EKENBERG, a subject of the King of Sweden and Norway, residing in Stockholm, Sweden, have invented 5 certain new and useful Improvements in Vacuum Apparatus, of which the following is a specification.

This invention relates to devices operating on the injector principle for evacuating chambers containing gases and gaseous vapors—such, for example, as air mixed with watery vapor—and, as such a device is or may be employed for exhausting a vacuum-pan, it is commonly called a "vacuum apparatus." 10 The object of the invention is to provide an injector device which will produce the maximum exhausting effect with a minimum quantity of liquid under pressure passing through the injector. In order to attain this result, 15 the jet employed is flattened or ribbon-like instead of being cylindrical in cross-section, and its dimensions in cross-section are proportioned substantially to the pressure on the liquid used. For example, with a flat jet having the dimensions of four to six millimeters wide and 0.5 to 0.6 millimeters in thickness 20 the pressure on the water or other liquid used would be from three to four atmospheres. The useful effect or duty of an injector device appears to be directly proportional to the periphery of the jet employed, and hence the best 25 results, proportioned to the amount of liquid used, will be attained with a thin flat ribbon-like jet.

30 In the drawings, which illustrate an embodiment of the invention, Figures 1, 2, and 3 are enlarged sectional views of the injector device of the apparatus, Fig. 1 being a longitudinal section at line E F in Fig. 3, Fig. 2 being a similar section at line A B in Fig. 1, 35 and Fig. 3 a cross-section at line C D in Fig. 2. Fig. 4 is a vertical axial section of the entire vacuum apparatus on a smaller scale. Figs. 5, 6, 7, 8, 9, and 10 are diagrams showing several forms which the capillary jet may 40 have in cross-section.

Referring primarily to Figs. 1, 2, and 3, 1 is the receiving portion of the nozzle of the injector device, and 2 is the discharging por-

tion thereof. The liquid, as water under pressure, enters the device at 3 in the part 1 and passes out at the gaged outlet 4 of said part. Opposite to and aligned with the outlet-passage 4 is the corresponding outlet-passage 5 in the part 2. The passages 4 and 5 will have the same dimensions in cross-section. The liquid under pressure entering the nozzle at 3 is forced through the passage 4 in a thin flat ribbon-like jet and enters the passage 5. In passing across the space between the parts 1 and 2 the jet or stream of liquid draws in with it the air or gas entering at apertures in the sides of the device, as indicated by the arrows seen in Fig. 1. So long as the jet-aperture is capillary and so thin and flattened as to offer a very extended lateral surface in proportion to its area of cross-section it need not necessarily be straight when seen in cross-section, as indicated in Fig. 3, where, at 5, is indicated the shape of the jet. It may have other forms, as represented by the diagrams. For example, Fig. 5 shows a straight or plain cross-section, in Fig. 6 it is zigzag, in Fig. 7 it is in the form of a circle, and in Fig. 8 it is in the form of a cross. In all of these forms, however, the width of the jet, as seen in cross-section, is many times greater than its thickness, and the thickness throughout is substantially uniform. Fig. 8 may be considered as two crossed flat jets, and there may be a group of such flat or ribbon-like jets. Fig. 9 shows a plurality of capillary jets arranged abreast, and Fig. 10 shows two parallel jets like that seen in Fig. 5.

Fig. 4 illustrates the application of the injector device to a vacuum-producing apparatus. In this figure, 7 is an upright vessel having in it superposed chambers 8, 9, 11, and 13. The liquid W—as water, for example—enters the upper chamber 8 at an inlet 8' under pressure. In the bottom of this chamber are set one or more injectors 15, (of the construction above described,) which extend down through an upper extension of the chamber 9 into an annular chamber 11. The chamber 9 receives the gases or air from the chamber in which a vacuum is to be formed through a pipe 10, and said gases circulate among tubes

12, which connect the chamber 11 with the lower chamber 13 through the gas-receiving chamber 9.

So far as described the operation is as follows: The water W passes from the chamber 8 under pressure down through the injector devices 15 into the chamber 11 and flows thence down through the tubes 12 into the chamber 13 and off to waste at the outlet 14. The air or gas entering the chamber 9 at the inlet 10 will in passing among the tubes 12 lose any water it may carry in the form of vapor, the vapor condensing on the colder tubes 12 and descending to the bottom of the chamber 9. The air or gas thus freed of its moisture rises into the upper part of the chamber 9 and is drawn in by the injector devices in the manner heretofore explained and carried with the jets of liquid flowing through said injector devices down into the chamber 11 and thence down through the tubes 12 into the chamber 13.

There is a centrally-disposed injector device 18 situated in a depressed portion 17 of the bottom 16 of the chamber 9, and this injector device is supplied from the chamber 8 by a pipe 19. This device drives out the liquid from condensation (if any) collected in the chamber 9.

There is a centrally-disposed bell 20 in the chamber 9 about the pipe 19. This bell covers the depression 17 and forms about it an annular chamber in the chamber 9, which contains the tubes 12. This bell device compels the entering gases to pass among the tubes before reaching the injector devices 15. The liquid of condensation flows to the depression 17 under the lower edge of the bell 20.

It may be well to explain that a capillary jet-passage in the device described has a technical effect quite distinct from the larger non-capillary tube. The purpose of the jet or stream of liquid, ordinarily water, is to carry with it the air, and the capacity of the capillary stream of water for this purpose over the ordinary stream consists in this: The ordinary stream from a non-capillary passage is either smooth superficially or slightly grooved (or fluted) parallel with its axis, while the stream from the capillary passage is grooved or corrugated transversely on its surface from surface tension of the liquid which tends to form as it emerges into a series of coalesced globules. This gives to the stream a laterally-

corrugated form which carries in with it the air in proportion far in excess of that carried in by the ordinary stream.

Having thus described my invention, I claim—

1. In an apparatus for the purpose specified, the combination of a vessel having in it a chamber to receive a liquid under pressure for operating an injector device, a chamber to receive air charged with moisture, injector devices for removing the air from said chamber, means in the air-receiving chamber for condensing the moisture in the air, and means for expelling the liquid of condensation from said chamber.

2. In an apparatus for the purpose specified, the combination of a vessel 7, having in it a chamber 8 to receive an injecting liquid under pressure, a chamber 9 with an inlet for air charged with moisture, an annular chamber 11, injector devices connecting the chambers 8 and 11, and adapted to receive air from the chamber 9, a lower chamber 13, condensing-tubes 12, extending through the chamber 9 and connecting the chambers 11 and 13, and means for discharging the water of condensation from the chamber 9 into the chamber 13, substantially as set forth.

3. In an apparatus for the purpose specified, the combination of the vessel 7, having in it an upper chamber 8, having an inlet for water under pressure, an annular chamber 11 below the chamber 8, a chamber 9, having an inlet for air or gases carrying moisture, said chamber 9 having an upper portion which interposes between the chambers 8 and 11, injector devices 15, connecting the chambers 8 and 11 and adapted to receive the air or gases from the chamber 9, a lower chamber 13, a plurality of condenser-tubes 12, connecting the chambers 11 and 13 and extending down through the chamber 9, and means for expelling the water of condensation from the last-named chamber, said means comprising an injector device 18, and a pipe 19, connecting the water under pressure in the chamber 8, with said injector device.

In witness whereof I have hereunto signed my name in the presence of two subscribing witnesses.

MARTIN EKENBERG.
